DESIGN FOR A KNITTED FABRIC

William J. Beniston, Seaford, N. Y., assignor to
Julius Kayser & Co., New York, N. Y., a corpo-
ration of New York

Application May 28, 1936, Serial No. 62,882

Term of patent 3½ years

To all whom it may concern:

Be it known that I, William J. Beniston, a citizen of the United States, residing at Seaford, Nassau County, State of New York, have invented a new, original, and ornamental Design for a Knitted Fabric, of which the following is a specification, reference being had to the accompanying drawing, forming part thereof.

The single figure of the drawing is a plan view of a piece of knitted fabric embodying my new design.

The design is characterized by a plurality of

series of short diagonal ribs raised from the normal surface of the fabric and connected with each other, each series extending across the face of the fabric and in conjunction with adjoining series, giving the appearance of diamond-shaped areas over the entire surface of the fabric as shown in the drawing.

I claim:

The ornamental design for a knitted fabric, as shown and described.

WILLIAM J. BENISTON.
